BAG TYPE GARMENT FINISHER

Annis R. Winter, Fort Worth, Tex.

Application April 26, 1948, Serial No. 23,355

3 Claims. (Cl. 223—67)

1

This invention relates to garment finishers and has reference to a bag type steamer.

An object of the invention is to provide an efficient bag type garment finisher which is economical in its construction, as well as one which is adaptable to finishing both long and short garments.

Another object of the invention is to provide, in a garment finisher of the referred to class, a construction and arrangement of parts whereby relatively dry steam may be applied to the inner areas of the garments being finished.

A further object of the invention is to provide an improved means for supplying heat to the interior of the inflated bag.

A particular object of the invention is to provide an inflated bag type garment finisher which may be readily reduced in height for shipping or storing.

These and other objects of the invention will become apparent from the following description of the accompanying drawings, wherein:

Figure 1 is a side elevational view of a bag type garment finisher embodying the features of the present invention.

Figure 2 is an enlarged vertical and broken sectional view of the front of the garment finisher illustrated in Figure 1 and having the bag thereof removed for better illustrating the construction.

Figure 3 is a broken sectional view of the blower which is a part of the present garment finisher, and

Figure 4 is a broken front elevational view of the heat exchanger which is a part of the blower mechanism illustrated in Figure 3.

The form of the invention shown includes a rectangular housing 1 having a rearwardly extending horizontal blower duct 2 which encloses and supports an electric motor 3 having a fan 4 attached to the shaft 5 of the said motor. As shown in Figure 3, the motor 3 is supported on angle irons 6 secured across the duct 2 and near the bottom portion thereof. The outer end of the duct 2 is covered with a large wire screen 7, the latter being retained by means of a flanged ring 8 on the periphery of the said duct.

The upper surface of the housing 1 has an annular opening 9 in the form of an upwardly extending and outwardly flanged ring 10. A bag 11 of flexible porous material such as heavy canvas, which generally conforms in shape with and is larger than the garments 12 to be steamed, is secured to the housing ring 10 by means of a band 13 around the said ring and over the lower

2

opened end of the said bag. As shown in Figure 1, the upper end of the bag may be tied or otherwise closed, as shown at 14.

Within the vertical center of the housing 1, there is a cylindrical tubular steamer 15 which extends upwardly through the housing opening 9 and into the lower portion of the bag 11. As shown in Figure 2, the tubular steamer 15 is provided with numerous upwardly and outwardly directed ports 16 whereby steam entering the said steamer will be moved in the directions indicated by the arrows. There is a partition 17 near the lower end of the steamer 15 to provide a moisture trap 18 below the said steamer. The lower end of the moisture trap 18 is partially closed and is connected with a downwardly directed pipe 19, which in turn is respectively connected with an elbow 20, a horizontally positioned check valve 21, a nipple 22, a steam trap 23, and a return pipe 24, connected with a boiler (not shown) or outlet. A horizontal steam supply pipe 25 is connected with the moisture trap 18 near the upper end of the latter. By means of elbows 26 and a connecting length of pipe 27, the moisture trap 18 is provided with a quick acting valve 28 which, by means of a tubular connection 29 and fittings 30 at each end thereof, is joined to the lower end of the tubular steamer 15. The valve 28 is operated by a foot pedal 31 outwardly of the housing 1, which pedal is pivotally supported within the housing by means of a U-shaped bracket 32 mounted on the base of the said housing. The bracket 32 is provided with a horizontal pin 33 for engaging the pedal 31 which connects with a rod 34 pivotally connected with the lever 35 of the valve 28.

A heat exchanger 36 is positioned within the housing 1 and over the inner end of the blower duct 2 and is comprised of a length of metal tube 37 bent along equal lengths thereof as shown in Figure 4, and provided with transverse vertical fins 38 for releasing heat from the said tube to the interior of the housing 1 when air from the fan 4 is blown over the same. As shown in Figure 2, the one end of the heat exchanger tube 37 is connected with the supply pipe 25 and with the nipple 22 in the return line 24, said connections being made by means of fittings 39.

The motor 3 may be connected with and controlled by a switch pedal 40 positioned outwardly of the housing 1, and since such connection may be readily made by anyone versed in the art,

the wiring between the said switch pedal 40 and the motor is not illustrated in the drawing.

As shown in Figure 1, vertical standards 41 and 42 are mounted on the forward and rear upper central portions of the housing 1. Each standard 41 and 42 is provided with holders 43 and 44, respectively, said holders each being comprised of substantially flat members arcuate in lateral cross section for engaging and holding the lapped edges of the garment opening in contact with the bag 11, and for similarly holding the splits of coat tails against the said bag. Both standards are provided with links 45 and 46 in their upper ends for pivotally engaging their respective holders 43 and 44. The rear standard 42 is comprised of telescoping members 47 and 48 for adjusting the height of the rear holder 44, which adjustment is carried out by means of a set screw 49 in the outer member 48 for engaging the inner member 47.

The upper end of the tubular steamer 15 is closed with the exception of upwardly and outwardly directed ports 50. The upper end of the steamer 15 is also provided with laterally projecting flanges 51 extending from each side of the said steamer end and has an inverted U-shaped bracket 52 secured thereon by means of screws 53. An upwardly extending rod 54 is secured to the center of the bracket 52 and is in axial alignment with the steamer 15. A transverse hanger 55 is provided at the upper end of the rod 54, which hanger is positioned within the bag 11 for supporting the garments and bag during the operation of the finisher.

In operation, the bag 11 is inflated by air from the fan 4, and since the said air passes over the heat exchanger 36, the air passing into the bag and outwardly therethrough is heated. The garment 12 to be finished is placed on the bag in the manner illustrated in Figure 1, and the holders 43 and 44 are positioned for holding the garment in place. By pressing the steam valve pedal 31, steam is upwardly and outwardly directed from the steamer 15, thereby raising the nap on the said garment and pressing the same. After the steaming operation the valve 28 is closed by releasing the pedal 31. The resulting hot dry air within the bag 11 dries the garment 12.

The accumulated moisture within the moisture trap 18 passes by the check valve 21 and into 50 the steam trap 23, from where it is discharged outwardly through the return pipe 24.

The described form of the invention may be made in many ways within the scope of the appended claims.

What is claimed is:

1. A garment finisher comprising: a housing having an opening in the upper surface thereof, a blower connected with the wall of the said housing, a heat exchanger within the said housing and over the inner end of the said blower, a porous bag formed to receive the garment to be finished thereon, said bag having an opening at its lower end, said bag opening being secured over the said opening in the upper surface of the said housing, a relatively short tubular steamer having upwardly and outwardly directed ports therein, said steamer being vertically positioned above the said housing and extending upwardly

5 into the said bag, a steam supply line connected with the said steamer, a vertical rod detachably secured at the upper end of the said steamer, and a hanger secured at the upper end of the said rod and supporting the upper end of said bag.

2. A garment finisher comprising: a housing having an opening in the upper surface thereof, a blower connected with the wall of the said housing, a heat exchanger within the said housing and over the inner end of the said blower, a porous bag formed to receive the said garment to be finished thereon, said bag having an opening at its lower end, said bag opening being secured over the said opening in the upper surface 10 of the said housing, a relatively short tubular steamer having upwardly and outwardly directed ports therein, said steamer being vertically positioned above the said housing and extending into the said bag, a moisture trap beneath the said steamer, means connecting the said moisture trap with the lower end of the said steamer, a steam supply line connected with the said moisture trap, a vertical rod detachably secured to the upper end of the said steamer, and a hanger secured 15 at the upper end of the said rod and supporting the upper end of said bag.

3. A garment finisher comprising: a housing having an opening in the upper surface thereof, a blower connected with and located outwardly of the wall of said housing, a vertically disposed heat exchanger within said housing and inwardly positioned relative to said blower, a porous bag formed to receive the garment to be finished thereon, said bag having an opening in its lower end, an opening in the upper surface of said housing and connected with said opening in said bag, a relatively short tubular steamer having upwardly and outwardly directed ports therein, said steamer being vertically positioned above said housing and extending into the lower end of said bag, a moisture trap positioned below said steamer, a steam supply line connected with the upper end of said moisture trap, a pedal operated valve also connected with the upper end of said moisture trap, a tubular means connecting said pedal operated valve with the lower end of said tubular steamer, a return line connected with the lower end of said moisture trap, said return line including a check valve adjacent said lower end of said moisture trap and a steam trap connected with said return line outwardly of said check valve, means connecting the one end of said heat exchanger with said supply line, and means connecting the remaining end of said heat exchanger with said return line between said check valve and said steamer trap.
